UNITED STATES PATENT OFFICE.

WALTER E. HUME, OF FAIRFAX COUNTY, VIRGINIA, ASSIGNOR OF ONE-FIFTH TO MARTIN P. GREENE, ONE-FIFTH TO MARTIN E. GREENE, AND ONE-FIFTH TO PERCY MCK. BALDWIN, ALL OF ALEXANDRIA, VIRGINIA, AND ONE-FIFTH TO GEORGE H. BEUCHERT, OF WASHINGTON, DISTRICT OF COLUMBIA.

BOX-FASTENER.

1,152,179.

Specification of Letters Patent. Patented Aug. 31, 1915.

Application filed June 15, 1915. Serial No. 34,262.

To all whom it may concern:

Be it known that I, WALTER E. HUME, a citizen of the United States, residing in Fairfax county, State of Virginia, have invented certain new and useful Improvements in Box-Fasteners, of which the following is a specification.

This invention relates generally to box fasteners, and particularly one adapted for securing the covers on plain packing boxes designed to be used for packing any commodity whose containers are to be returned to original shipper in same box.

The object of the invention is to provide an article of this character which shall be thoroughly effective in attaining the purpose for which it is designed; which may readily be applied to position and positively held in place against unauthorized removal without detection; which will indicate any attempt at having been tampered with; and which shall be simple of construction, easy to manufacture and cheap to produce.

With the above and other objects in view, as will appear as the nature of the invention is better understood, I have produced a box fastener embodying, generally stated, a shank having a spur or prong at one end, a loop at its other end, and a seal wire receiving opening at an intermediate point. Generally it will be preferred to have the fastening members counterparts of each other, thus to reduce the cost of production to the minimum and to facilitate installment of the parts. The members will be made of flexible metal to permit bending to desired contours, and non-resilient to eliminate danger of breakage or fracture.

Further and novel features of the invention will hereinafter appear.

In the accompanying drawing forming a part of this application and in which like characters of reference indicate corresponding parts:—Figure 1 is a view in perspective, partly in section, displaying the manner of applying one form of the invention to position; Fig. 2 is a detail view of the fastener shown in Fig. 1; Fig. 3 is a view in elevation of a modified form of the invention; Fig. 4 is a view in sectional elevation displaying the manner in which the fastener shown in Fig. 3 is applied.

Referring to the drawing, and to Figs. 1

and 2 thereof, C designates a portion of the cover of a box and W a part of one of its side walls, and as these parts may be of the usual or any preferred construction, further description is deemed unnecessary.

The fastener embodies two members, each a counterpart of the other, and each, as shown in Fig. 2, is constructed of wire formed at one end with an elongated loop 1, and at its other end with a prong or spur 2, the intermediate portion being twisted to form a shank 3 including an eye 4, the article, when supplied to the trade being flat or straight except for the spur.

In positioning the fastener, prior to securing the cover to the box, the former is provided with an orifice c and the latter with an orifice w. The shanks of the two fasteners are now passed through the orifices from the outer side of the cover and of the box wall, and then bent to lie flat with the parts, after which the spurs are driven to their seats. The cover having been secured in place, the loop 1 on the cover is bent down over the edge of the latter, and the loop of the fastener on the box is passed through the downturned loop and then rebent, as shown in Fig. 1, thus securing the two loops in interlocked relation. A seal wire S is now threaded through the eye of the fastener on the box and through its downturned loop, and the ends of the wire are secured by an ordinary leaden seal s.

In the modified form of the invention shown in Figs. 3 and 4, the fastening members are constructed of sheet metal and are not counterparts except that each is provided with an attaching spur 5 and the manner of assembling the members with cover and box is the same as that above described, namely, by the spurs and the openings c and w. One of the members, in this instance, that secured to the cover is provided with a loop in the nature of a head 6 having a transverse slot 7 to receive the downturned end 8 of the other member, the end 8 being provided with an orifice 9 and the intermediate portion of the member with a pair of orifices 10, and through these orifices the sealing wire S is threaded and secured as described.

In both embodiments of the invention, it will be obvious that without destroying one

or the other of the fastening members, or severing the seal wire, it will be impossible to remove the cover, so that the effective sealing of the box is readily secured.

5. What is claimed is:—

1. A box fastening member comprising in a one-piece structure a shank having a spur at one end, a closed end loop at its other end forming an integral continuation 10 of the shank and a seal-wire receiving opening at an intermediate point.

2. A box fastening member comprising in a one-piece structure a twisted shank having a closed end loop at one end, a spur at 15 its other end forming an integral continuation of the shank and an intermediate seal-wire receiving opening.

3. The combination with a box wall and its cover, each provided with an opening, of 20 fastening members having their shanks

passed through the openings and secured to the inner surfaces of the parts, the outer ends of the members being interlocked, and a sealing wire securing the outer terminal of one member with an intermediate part. 25

4. The combination with a box-wall and its cover, each provided with an opening, of fastening means comprising two members each having a loop at one end, a spur at the other end and an intermediate eye, the 30 spurred ends being passed through the openings and secured to the box parts, and their outer ends being interlocked.

In testimony whereof I affix my signature in presence of two witnesses.

WALTER E. HUME.
